UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed March 27, 1925. Serial No. 18,760.

To all whom it may concern:

Be it known that I, NORMAN B. Hurd, a citizen of the United States of America, residing at New Britain, Connecticut, have invented a new and useful Lock, of which the following is a specification.

My invention relates to a lock particularly, though not exclusively, adapted for use on hotel doors and the like.

10 It is an object of the invention to provide a lock which when locked from the inside when a door bearing the lock is closed may not be unlocked from the outside except by means of a special emergency key, and if 15 locked from the inside while the door is open, the mere closing of the door will position the lock parts so that the door may be unlocked from the outside by an ordinary key.

20 It is a further object to provide a lock in which tumbler dogging means may be movably mounted in the lock case so as to be movable to an inoperative and an operative position.

25 It is a further object to provide a lock in which a stump or fence may be movably mounted and controlled by means such as an auxiliary latch.

Other objects will hereinafter appear.

30 Briefly stated, in the preferred form of the invention I employ a lock having a latch or the like and within the lock case is provided means for locking the latch in projected position. The locking mechanism 35 within the case may be such that when a door is locked from the inside the locking parts are moved to such positions that an ordinary or maid's key, for example, may not be effective to enter a room from the outside 40 but an emergency key may be successfully employed for that purpose. Means such as a tumbler serves to dog or block the locking mechanism in the forward or projected position and in order to dog the tumbler I 45 employ a tumbler dogging means such as a stump or fence which is movably mounted in the case so as to be movable to an operative and an inoperative position. I prefer to control the movable stump by means such as 50 an auxiliary latch which may move or permit movement of the same to an operative position when the auxiliary latch is retracted as by the strike plate and which may move or permit movement of the movable stump

to an inoperative position when the auxiliary 55 latch is projected. With such an arrangement, if the latch locking mechanism should be thrown to projected position from the inside while the door is open, the stump, which dogs the locking mechanism would be in an 60 inoperative position so that the locking mechanism would not be blocked and the latch would be permitted to be retracted on coming against the strike plate. This action 65 then of closing the door would throw the locking mechanism back into position to be actuated by a maid's key from the outside.

In the drawings which show, for illustrative purposes only, a preferred form of 70 the invention:

Fig. 1 is a view in side elevation of a lock with the cover removed and illustrating the parts in position to be opened from the outside by an ordinary key;

Fig. 2 is a view similar to Fig. 1 but 75 illustrating the positions of the parts when the door has been locked from the inside but the door being in open position, that is, the latch members out of contact with the strike plate;

Fig. 3 is an isometric view of a lock case and certain interior parts relatively separated for the sake of clear illustration;

Fig. 4 is a sectional view taken substantially in the plane of the line 4—4 of Fig. 1;

Fig. 5 is an inside end view of a cylinder lock which may be employed on the outside of the door;

Fig. 6 is a view similar to Fig. 5 but illustrating parts in a different position.

In said drawings, 1 indicates a lock case having a face plate 2 thereon. Suitable door latching means such as a latch 3 may extend through the face plate 2 and may be retracted as by means of the usual yoke 4 and door knob roll back 5. In the preferred form the roll back 5 is connected only to the inside knob and the outside knob, if one be provided, would be dead and would serve merely as a convenient handle, and would not be connected to the latch retracting mechanism.

I preferably employ a slide bolt 6 slidable in the casing and guided as by means of a pin 7 extending into a slot 8. The slide bolt may also have a second slot 9 positioned over a pin on an auxiliary latch lever 10 to be later described. The lower end of the slide bolt may have a projection or finger 11

to engage behind the plate or lug 12 on the latch bolt so that when the slide bolt is in the position indicated in Fig. 1 the latch bolt will be free to be moved to retracted position and with the slide bolt in the position shown in Fig. 2 the latch bolt will be locked against retractile movement.

A suitable tumbler 13 may be mounted upon the slide bolt as by means of the 10 aperture 14 and lug or pin 15 projecting from the slide bolt. The slide bolt may have a notch 16 therein to receive a projection 17 on the free end of the tumbler 13. A spring 18 serves to urge the tumbler in a counterclockwise direction as viewed in the drawings and this movement is limited by the projection 19 at one side of the notch 16 on the slide bolt. The tumbler 13 is gated as by means of a lug 15 20 thereon which lug engages a suitable stump or fence. Now in the usual form of lock, the fence or stump cooperating with the tumbler to dog the same is cast integrally with or fixedly secured to the 25 lock case. In the present instance, however, the stump or tumbler dogging means 21 which cooperates with a tumbler projection 20 is movably mounted in the case.

In the form shown I employ what may 30 be termed a stump lever 22 pivoted as by means of a pin 23 in the lock case and carrying the stump 21 at the other end. This stump lever I prefer to control by means of an auxiliary latch mechanism 35 having a purpose to be later described. 24 is a lever pivotally mounted in the case on the pin 25. An auxiliary latch 26 is secured to the lever 24 and moves with it. A spring 26 serves to urge the auxiliary 40 latch 26 to the outward or projected position. In the form shown the auxiliary latch carrying lever 24 has a cam surface 27 which when the auxiliary latch is being retracted and consequently moving the lever 24 toward the right as viewed in several figures, rides up on the tumbler stump 21 or the cam surface 28 on the lever 22. When the auxiliary latch 26 is moved 45 toward the left as viewed in the drawings by means of the spring 26, the rear side of the latch lever 24 engages a projection 29 on the stump lever 22 and thus serves to elevate the stump 21 to an inoperative position, for example, as shown in Fig. 2.

Now it will be seen that when the auxiliary latch is in retracted position as shown in Fig. 1, the cam surface 27 will have depressed the stump 21 to an operative position in front of the tumbler lug 20 and the slide bolt 6 will then be held in the retracted position shown in Fig. 1. When the door carrying this lock is closed it is obvious that the auxiliary latch being in engagement with the strike plate will remain in retracted position as shown in Fig.

1. Now if the slide bolt should be moved to the locking position indicated in Fig. 2 while the door is open there would be nothing to hold the auxiliary latch retracted and the stump 21 would then be elevated to an 70 inoperative position as shown in Fig. 2. In this position, therefore, the tumbler and slide bolt would not be dogged and the mere act of closing the door against the strike plate would cause the latch 3 to act 75 through the latch bolt and plate 12 to engage the finger 11 and thus retract the slide bolt and the parts carried thereby. The various parts would then again occupy the positions shown in Fig. 1. 80

Now, as has been stated, the outside door knob is merely a handle and does not at any time serve to withdraw the latch 3. From the outside latch 3 is always retracted by a suitable key. In the form 85 illustrated, the slide bolt may carry a lever 30 pivoted on the pin 15 and extending over the end 31 of a lever 32 which may be pivoted on a pin 33, carried by the slide bolt. The lower end of the lever 32 engages 90 21 which cooperates with a tumbler projection 20 is movably mounted in the case. 95

Now referring particularly to Fig. 4, 35 indicates a cylinder lock screwed into the lock case from the outside and carrying a cam or roll back 36 on the plug of the lock cylinder as will be understood. The roll back 36 is slotted and carries a plate 37 having a button or auxiliary roll back 38 100 which may be moved to either of the positions shown in Figs. 5 or 6. When a maid's key or a guest key is inserted in the plug of the cylinder lock 35, the plate 37 will not be moved for the reason that such key is too short to extend through the plug and beneath the plate 37. The button 38 will therefore remain in its extreme inward position shown in Fig. 5. With the auxiliary roll back 38 in the position shown in Fig. 5, 105 the same will be in a position to engage the top of the lever 30 when the parts are positioned as shown in Fig. 1. The roll back 36 and auxiliary roll back 38 may therefore be actuated by a guest or maid's key to depress the lever 30 and through the lever 32 retract the latch bolt so that the door may be 110 entered. 115

Referring now again to Fig. 4, 40 indicates an inside cylinder lock carrying a plug with an inside roll back 41 which is in position at all times to engage the projection 17 on the tumbler 13 for depressing the same and is also in position to engage the sides of the notch 16 in the slide bolt for moving the same. Now when the door has been entered and closed, the guest key may be inserted in the inside cylinder lock 40 and the plug turned so as to cause the roll back 41 to 120 first depress the projection 17 from the pos- 125 130

tion shown in Fig. 1 so as to disengage the tumbler projection 20 from the stump 21, which is now held in operative position as shown in Fig. 1; further rotation then of 5 the inside key will cause the roll back to move the slide bolt 6 toward the left as viewed in Fig. 1 until it reaches the position shown in Fig. 2 with the roll back 41 brought up against a suitable stop 42 carried by the casing. During this movement 10 it will be observed that the levers 30, 32 have been carried along toward the left with the slide bolt. In the position shown in Fig. 2 the levers 30, 32 would be completely out 15 of the path of movement of the roll backs on either the inner or outer cylinder plugs. It will thus be plain that if the maid's key be inserted in the outside cylinder, the plug may be freely rotated completely around 20 without engaging the lever 30 and since only the auxiliary roll back 38 extends over the tumbler projection 17, the same would not be depressed.

Now in case of emergency, a door locked 25 from the inside may be entered with the aid of a special emergency key which is made long so as to extend through the plug of the outside cylinder 35 and elevate the plate 37 and the auxiliary roll back 38 to the position shown in Fig. 6. With the auxiliary roll back 38 in such projected position if the plug now be turned, the auxiliary roll back 30 will engage the tumbler projection 17 and 35 will move the same downwardly so as to disengage the projection 20 from the stump 21 and further rotation will cause the auxiliary roll back 38 acting against the right hand side of the notch 16 to again move the slide bolt back to the position shown in 40 Fig. 1, and upon a still further rotation the auxiliary roll back will engage the top of the lever 30 and as previously described will retract the latch 3. With the parts again in the extreme right hand position as viewed 45 in Fig. 1 either the guest or the maid's key may be used to enter the door from the outside.

While the invention has been described in some detail and specific illustrations of 50 its use defined, I do not wish to be confined to the form of lock herein shown, since the invention as defined in the appended claims

may be variously embodied, however, I wish to lay particular stress upon dogging means such as the stump which is movably mounted 55 instead of being forming integrally with the lock case as is the usual practice.

I claim:

1. In a lock, a lock case, a latch in said case, a slide bolt in said case for locking 60 said latch in projected position, a tumbler carried by said slide bolt for locking the same in one position, and a stump cooperating with said tumbler for dogging the same in one position, said stump being movably 65 mounted so as to be movable to an operative and an inoperative position.

2. In the combination defined in claim 1, and an auxiliary latch means for cooperation with said stump for moving the same to an 70 operative position when the auxiliary latch is retracted.

3. In a lock, a lock case, door locking mechanism therein, a stump movably mounted in the case for dogging said door locking 75 mechanism in locked position, and an auxiliary latch for moving said movably mounted stump into position to dog said door locking mechanism.

4. In a lock, a lock case, door locking 80 mechanism therein, a stump for dogging said door locking mechanism, and an auxiliary latch means for cooperation with said movably mounted tumbler stump and serving to move the same to an operative position 85 when the auxiliary latch is in one extreme position and to an inoperative position when the auxiliary latch is in the other extreme position.

5. In a lock, a lock case, door locking 90 mechanism therein, a stump movably mounted in said case and adapted when in one position to dog said door locking mechanism, and an auxiliary latch means for moving 95 said stump to an inoperative position when the auxiliary latch is in projected position.

6. In a lock, a lock case, door locking mechanism therein, a lever pivotally mounted in said case and carrying a stump for dogging said door locking mechanism and auxiliary latch means for cooperation with 100 said lever carrying said stump for controlling the position of same.

NORMAN B. HURD.
